UNITED STATES PATENT OFFICE.

FRANK CLARK, OF THROOP, PENNSYLVANIA, ASSIGNOR OF ONE-HALF TO WILLIAM WETTON, OF THROOP, PENNSYLVANIA.

AERONAUTICAL MACHINE.

1,233,982.

Specification of Letters Patent. Patented July 17, 1917.

Application filed October 19, 1916. Serial No. 126,574.

To all whom it may concern:

Be it known that I, FRANK CLARK, a citizen of the United States, and resident of Throop, in the county of Lackawanna and 5 State of Pennsylvania, have invented certain new and useful Improvements in Aeronautical Machines, of which the following is a specification.

My invention relates to aeronautical machines and more particularly to a machine of this character to be used in warfare.

The principal object of the present invention is to provide an aeronautical machine which is started from the ground to sail in 15 the direction of the enemy and which will release bombs or other projectiles at intervals.

Another important object of the present invention is to provide a mechanism that 20 will turn the machine on its homeward flight after the last bomb or other projectile has been released therefrom.

An additional object of the invention is to provide means for automatically controlling 25 the planes of the machine.

A further object of my invention is to provide a novel means for retaining the bombs in position to be released one at a time.

30 Another object is to provide a machine of the type which consists of few parts and which may be built at a comparatively small cost.

With the above and other objects which 35 will become apparent as the description proceeds, the invention consists in the combinations, constructions and operations that will be hereinafter set forth in detail.

On the drawings,
40 Figure 1 is a side elevation of a machine constructed in accordance with my invention.

Fig. 2 is a rear end view of the same.
45 Fig. 3 is a detail view showing the means for controlling the planes.

Fig. 4 is another detail view of this mechanism.

Fig. 5 is a top view of the machine.
50 Fig. 6 is a top view of the machine with the planes and gas bag removed.

Fig. 7 is a detail view of one of the bomb holding members and the means for actuating the same to release the bombs.

Like characters of reference indicate like 55 parts in all the views.

Referring more particularly to the drawings, the numeral 5 designates the framework of the machine which is shown in this case as being rectangular. This frame is constructed from any light but durable material and has mounted therein a double walled gas bag 6 which is provided with a relatively large opening 7 that extends the entire length of the bag. The purpose of this relatively large opening 7 is to keep the 60 machine in a straight course which is accomplished by the air rushing through this opening. Extending longitudinally through the opening 7 is a propeller shaft 8 having the usual propellers 9 keyed thereto and the 65 usual motor 10 mounted thereon for driving this shaft.

Extending transversely across the top of the machine and having its ends journaled therein is a rotatable rod 11 having the usual 70 planes 12 fixed thereto. One of the rear end bars of the frame is U-shaped in cross section and has bearings 12 formed thereon. Mounted in this U-shaped bar or guide is a rack bar 13 having its upper end pivotally 75 connected with a link 14 which in turn is pivotally connected with the main plane. A pinion 15 is journaled in the bearings 12 and meshes with the rack bar 13. A sprocket chain 16 transmits power from the 80 shaft 8 to the pinion 15.

Journaled in bearings 17 which are secured to the bottom of the frame 5 is a shaft 18 which is threaded almost its entire length and has keyed thereto a relatively large 90 sprocket wheel 19 which is driven by a sprocket chain 20 from the shaft 8. Extending longitudinally through the frame and secured to the bottom thereof are parallel spaced bars or strips 21. Pivotally 95 mounted upon these bars 21 are bomb holding devices which comprise arcuate jaws 22 which have formed integral therewith arms 23. These arms 23 are inclined toward each other and are normally held in position for 100 grasping the bombs by means of contractile springs 24 which are attached at one end to the bars 21. An inverted U-shaped member 25, having a threaded opening therein, is mounted on the threaded portion of the 105 shaft 18 and is adapted to move longitudinally thereon. Disposed above the shaft 18 is a guide rod 26 which extends through an opening in the U-shaped member 25. As this inverted U-shaped member 25 passes 110

over the inclined arms 23 of the bomb grasping devices, it will move these arms toward each other and thereby release the bombs.

A rudder 27 is mounted at the rear end 5 of the machine and is normally held at right angles thereto by means of contractile springs 28. This rudder is provided with the usual rudder shaft which is provided with an angular extension 29.

10 The operation of the machine is as follows: The engine 10 is started to drive the propeller shaft 8 which drives the machine forward. Power is transmitted from this shaft 8 to the pinion 15 by means of the 15 sprocket chain 16 which will cause the rack bar 13 to move downwardly which will cause the planes to be moved in the position shown in Fig. 1. While the machine is thus, in motion, the threaded shaft 18 is rotated 20 by means of the sprocket chain 20 passing around the sprocket 19. This causes the inverted U-shaped member 25 to move longitudinally on this shaft and when the ends of this member 25 contact with the ends of 25 the arms 23 of the bomb holding devices, they will be moved slightly toward each other. This will open the jaws 22 thereby releasing the bombs. After the last bomb has been released, the member 25 engages 30 the member 29 and moves the same just enough to move the rudder against the tension of the springs 28 which will allow the machine to turn on its homeward flight. It

is to be understood that this member 25 only contacts with the member 29 just long enough for the turn to be made. By the time the machine has been turned on its homeward flight, the member 25 will have reached the end of the threaded shaft.

Having described the form of my invention which I now consider to be the best embodiment thereof, it is to be understood that the same may be modified in many different respects, that may fairly fall within the scope of the appended claim. 40 45

What is claimed is:

The combination with a flying machine including a rudder, of resilient means normally retaining the rudder in a position to cause the machine to travel in a straight 50 path, spaced longitudinal bars mounted on the machine, projectile holding means mounted on the bars and normally retained in engagement with projectiles, the projectile holding means being disposed so as to 55 retain the projectiles between the spaced bars, an angularly disposed extension fixed to move with the rudder, and a longitudinally movable member mounted on the machine adapted to engage the projectile holding means and successively release the projectiles, said member engaging the angularly disposed extension after the last projectile 60 has been released, to move the rudder to a new position.

FRANK CLARK.
